UNITED STATES PATENT OFFICE.

OTTO L. SWANZEY, OF ST. LOUIS, MISSOURI.

APPARATUS FOR PRINTING ON HATS.

Application filed June 10, 1925. Serial No. 36,115.

This invention relates to apparatus for printing advertisements or other matter on hats, and has for its principal object the production of an extremely simple means 5 for printing on hats, particularly straw hats, whereby said hats may be distributed for advertising purposes.

For some time prior to this invention it has been realized that straw hats of the type 10 used by farmers in the field and other persons whose work keeps them in the sun much of the time on which advertisements were printed would constitute a very excellent advertising medium. However, because of the nature of the material of which 15 said hats are made and due to the fact that such hats must necessarily be printed after they are made up in their circular form, no method nor apparatus had been developed 20 prior to this invention which would permit the entirely successful printing on said hats.

Most of the cheap farm or harvest hats are imported in rough hat form from foreign 25 countries, such as Island of Java, Mexico, Dutch West Indies, and other countries, and said hats are usually already made up when received in the United States from the manufacturers. In view of the foregoing, 30 any device for printing on said hats must be capable of printing on a convex surface.

For many years cloth caps have been distributed on which advertisements were 35 printed, but the difficulties encountered in connection with printing on straw hats were not met with in printing said caps for the reason that the cloth from which the caps were formed was printed in flat form 40 before the caps were made. In connection with straw hats, however, it is not possible to print on the material before the hats are made up.

Attempts were made prior to this invention 45 to flatten the curved walls of straw hats and print on said walls while they were so flattened, but this method resulted in failure for the reason that after an impression had been made and the type was being 50 withdrawn the wall of the hat would immediately return to its original curved condition, said hat wall following the type, and consequently the impression would be smeared.

In view of the difficulties set forth above, 55 I have evolved the apparatus disclosed in

the present application, which provides a very simple and inexpensive means for printing on hats which have already been shaped; thus making it possible for manufacturers and dealers to distribute a very useful article to the trade which carries with it a tremendous advertising appeal. 60

With the foregoing and other objects in view, the invention comprises the novel construction, combination and arrangement of parts hereinafter more specifically described and illustrated in the accompanying drawings, wherein is shown the preferred embodiment of the invention. However, it is 65 to be understood that the invention comprehends changes, variations and modifications which come within the scope of the claim hereunto appended.

Fig. I is a front elevation of my improved hat printing apparatus, a hat being shown in section. 70

Fig. II is a side elevation of the apparatus illustrated in Fig. I, in this view also a hat being shown in section. 75

Fig. III is a view of a hat on which an advertisement has been printed by my improved apparatus. 80

In the drawing, A designates my improved apparatus for printing on straw hats which comprises a base member 1 which supports a front plate 2 and a rear plate 3, said plates 2 and 3 being secured to said base member 1 and being extended upwardly therefrom. The plates 2 and 3 are 85 secured together by means of a pair of brackets 4 whereby said plates are given the required rigidity to support the mechanism of the apparatus. 90

Supported by the plates 2 and 3 is a shaft 95 5 which is rotatably mounted in suitable bearings 6 supported by said plates. The forward end portion of the shaft 5 extends some distance beyond the front plate 2 and mounted on said forward end portion of said shaft is a block 7, said block being preferably approximately round in front elevation (Fig. I) and being fixed to the shaft 5 so that it will rotate therewith. Arranged above the shaft 5 in approximately 100 vertical alignment therewith is a shaft 8, said shaft 8, like the shaft 5 already described, being mounted in suitable bearings 9 fixed to the plates 2 and 3 and said shaft 8 being capable of rotary movement. Se- 105 cured to the outer portion of the shaft 8 is 110 the type supporting member of my im-

proved device, said member comprising a hub portion 10, arms 11 and a portion 12 having an arcuate face 13 on which the printing member 14 provided with type 15 is arranged. The printing member 14 and type 15 may be formed of any suitable material, such, for instance, as rubber, and the type holder is so arranged with respect to the block 7 that when the shaft 8 is rotated the type 15 will move along a curved line which passes a very slight distance from the periphery of the block 7. 16 designates an operating handle by means of which the shaft 8 may be conveniently rotated.

In the use of my improved hat printing apparatus the type supporting member and the handle 16 associated therewith are moved to the position in which they are shown by dotted lines in Fig. I of the drawing, after which a hat B is drawn over the block 7 as shown in Figs. I and II, the brim B' of said hat being located adjacent to the front plate 2 and the block 7, which is so shaped that it will fit closely within the crown of said hat, being located within said crown of said hat. When the hat B has been arranged in place as described, the shaft 8 is rotated by moving the handle 16 until an end of the printing member 14 contacts with the crown of the hat B. The movement of the type supporting member is continued after this contact is made and this continued movement will cause rotary movement to be imparted to the hat B and block 7, whereby impressions of the type 15 will be made.

on the hat. It will be noted that because the hat B and type 15 are moving at the same speed, there will be no relative movement between said elements and therefore a clear unsmeared impression of the type will 40 be obtained on the hat.

It is apparent that my improved apparatus will be provided with some sort of an inking device, but as these devices are common and because the inking device forms no 45 part of the present invention, I have not illustrated same in the drawing.

While I have described an apparatus for printing straw hats, it is apparent that felt hats, or hats of any other material may be 50 printed by my improved device.

I claim:

An apparatus for printing on a hat which comprises a rotatable member adapted to receive a hat, said rotatable member being of 55 such shape that it will fit relatively closely within the crown of said hat and a second rotatable member having arcuate faces on which printing type are arranged, the second mentioned rotatable member being capable 60 of being rotated while varying portions of the type thereon are in contact with the hat on the first mentioned rotatable member whereby said hat is rotated and impressions of said type are placed on said hat during 65 the rotation thereof.

In testimony that I claim the foregoing I hereunto affix my signature.

OTTO L. SWANZEY.
